UNITED STATES PATENT OFFICE.

JAMES A. McLAUGHLIN, OF BRUNSWICK, GEORGIA.

LOG-TURNER FOR SAW-MILLS.

SPECIFICATION forming part of Letters Patent No. 439,822, dated November 4, 1890.

Application filed December 31, 1889. Serial No. 335,480. (No model.)

To all whom it may concern:

Be it known that I, JAMES A. McLAUGHLIN, a citizen of the United States, residing at Brunswick, in the county of Glynn and State of Georgia, have invented certain new and useful Improvements in Log-Turners for Saw-Mills; and I do hereby declare the following to be a full, clear, and exact description of the invention, such as will enable others skilled in the art to which it appertains to make and use the same.

This invention relates to log-turning apparatus for saw-mills; and it consists in certain improvements in the construction of the same, as hereinafter described and claimed.

In the accompanying drawings, Figure 1 is a plan view of a log-turning apparatus provided with my improvements. Fig. 2 represents an end view of the same. Figs. 3 and 4 illustrate the turn-blocks.

A designates the skids, which are placed to extend at right angles from the log-carriage B. The ends of the skids which are adjacent to the carriage are beveled and recessed or cut out to receive the guides C, which are fixed in inclined positions, as shown.

D indicates a series of pushers, each of which is placed between two guides C, and is provided with a rack bar or teeth a, through which the pusher may be engaged by a pinion or a toothed segment b, which is fixed to a rotative shaft E. A wheel F is carried by each of the pushers, being mounted in the upper end thereof, as shown.

The shaft E is mounted in position parallel with the line of the log-carriage, and to said shaft is secured a lever J, by means of which the shaft may be turned and the pushers raised by the action of the segments b, which

connect with the teeth a.

I indicates a notched quadrant for securing the lever J in position at any desired point.

L indicates a counter-balance secured to the shaft E for assisting in the operation.

The log G being in position on the head-blocks H, as seen in Fig. 2, is usually moved back somewhat before being turned, and the object of the invention is to effect this lateral movement of the log uniformly and readily. Such lateral movement is produced by turning the shaft E by means of the lever J, whereby the several pushers may be raised, the segments b, engaging with the teeth a, and the wheels F, impinging against the log as the pushers move upward in their guides. The log being thus pushed back, as required, may be turned to the required position by means of a cant-hook M. (Shown in Fig. 2.)

I claim—

1. In a saw-mill, the supporting timbers or skids, which are recessed and provided with guides, in combination with a series of pushers placed within said guides and provided with wheels F and teeth a, and a rotative shaft provided with fixed toothed segments in position to connect with the teeth of the pushers, whereby the latter may be raised, substantially as and for the purposes described.

2. The combination, with the recessed skids A, provided with guides C, of the pushers D, provided with teeth a, wheels F, mounted on said pushers, rotative shaft E, provided with segments b, in position to connect with the teeth a, and a lever connected with said shaft, substantially as set forth and described.

In testimony whereof I have affixed my signature in presence of two witnesses.

JAMES A. McLAUGHLIN.
